UNITED STATES PATENT OFFICE.

OTTO L. HEEGER, OF ST. PAUL, MINNESOTA.

ELECTRIC FLASHER.

1,174,007.

Specification of Letters Patent. Patented Feb. 29, 1916.

Application filed April 19, 1915. Serial No. 22,338.

To all whom it may concern:

Be it known that I, OTTO L. HEEGER, a citizen of the United States, residing at St. Paul, in the county of Ramsey and State 5 of Minnesota, have invented a new and useful Improvement in Electric Flashers, of which the following is a specification.

My invention relates to an improved flasher, the primary object being to provide 10 a device for the purpose of amusement by means of which an electric circuit is closed and opened to produce a flash of light when a person strikes the device against an object, the blow automatically causing the 15 closing and opening of the circuit for the amusement of the spectators. The device is adapted to produce upon the stage the act or play, the device being so arranged as to provide flashing of light for scenic 20 effects.

In the accompanying drawing forming part of this specification, Figure 1 is a longitudinal section of my invention; Fig. 2 is a section taken upon the line X—X of 25 Fig. 1; Fig. 3 is a section taken on the line Y—Y of Fig. 1, and Fig. 4 is a plan of a detail of my invention.

In the drawing, 2 indicates a head made of wood or other suitable insulating material having a flat surface 3 and curved lower surface 4, said head acting as a weight and serving to hold a terminal piece 5 of an electric circuit in a well 6 which is formed in the head. Fastened in an opening 7 in the side of the head and projecting laterally therefrom is a flexible handle member 8 made of ratan or other suitable material which is adapted to bend or yield when held in the hand and the head struck 35 down. Laid longitudinally along the lower side of this handle member is an insulated conducting wire 10 leading from a conducting cord 11 to a binding screw 12 on the side of the head 2, the shank of said binding 40 screw extending into said well and making connection with the terminal 5. Mounted upon the upper side of the handle member 8 opposite to the conductor 10 is a long flexible switch arm 13, the stationary end 45 of which being insulated and connected to the electrical conductor 14 leading from the conducting cord 11. The conductor 10 and switch arm 13 are secured over the handle member 8 by an outer cover or jacket 15 of insulating material, said cover binding the switch arm and conductor 10 firmly on

the handle. The insulating body of the conducting cord 11 is stripped from the conductors 10 and 14 a short distance back from the stationary end of the handle 8 and the 60 readily flexible portion of the conductors 10 and 14 extending between the end of the handle member 8 and the cord is thinly insulated so that a freely flexible joint is produced enabling the user to move freely 65 manipulate the device without bending the cord 11. The outer covering 15 extends back over the cord 11 leaving a space within which the intervening portion of the conductors 10 and 13 between the cord and handle is free to play when the handle is struck by its head against an object. The free end of the switch arm 13 is formed with a weighted contact point 16 which normally 70 is out of contact with the terminal 5, but strikes down against said terminal and completes the circuit when the head strikes by 75 its curved surface against an object. The terminal 5 can be made out of carbon, calcium carbide or other suitable material, 80 which owing to its composition is adapted to create a vivid flash of light when the switch arm closes an electric circuit. The contact point 16 likewise can be made out 85 of metal or any other suitable material.

When the terminal 5 becomes worn away, it can be replaced by a fresh terminal by loosening the screw 12. In operation the conductors 10 and 14 are connected with a suitable source of current such as derived 90 from a lighting circuit or a battery and the flasher is held by its handle and struck by the lower surface 4 of its head against an object, the sharp impact causing a switch 95 arm 13 to swing downwardly and the point 16 to close the circuit. Immediately the spring arm 13 flies back thus interrupting the circuit and producing a sharp flash. The device owing to its flexibility can be 100 easily manipulated by the user, the hinge connection formed by the flexible connection intervening between the handle proper and the conductor cord allowing the device to be freely operated.

In accordance with the patent statutes, I 105 have described the principles of operation of my invention, together with the apparatus which I now consider to represent the best embodiment thereof, but I desire to have it understood that the construction 110 shown is only illustrative, and that the invention can be carried out by other means

and applied to uses other than those above set forth within the scope of the following claims.

Having described my invention, what I claim as new and desire to protect by Letters Patent is:

1. A flasher, comprising, in combination, a head member formed with a well, an electrical terminal removably held in said well by said head, a flexible handle member extending laterally from said head, a flexible switch arm held upon said handle with its free end adapted to make contact against said terminal, but normally urged out of contact, an electrical conductor cord having conductors connected with said switch arm and said terminal and an insulating cover holding the stationary portion of said switch arm and the conductor leading to said terminal on said handle, said cover extending back over said cord, the end of said cord adjoining said handle being spaced from the handle to permit the conductors bending freely and forming a laterally flexible joint between said cord and the handle.
2. A flasher, comprising, in combination, a head member formed with a well, an electrical terminal held in said well with its

upper end exposed, a handle upon which said head is mounted, a flexible switch arm 30 carried by said handle with its free end adapted to spring down against said terminal and normally urged out of contact with said terminal and electrical conductors connected to said switch arm and said terminal, 35 said switch arm and terminal when closed being adapted to complete an electrical circuit passing through said conductors.

3. An electrical flasher, comprising, in combination, a holder, an electrical terminal 40 supported by said holder, a flexible switch arm supported by said holder with its free end adapted to contact with said terminal and normally urged out of contact, said switch arm and terminal being adapted to 45 close an electrical circuit when said holder is struck against an object and to instantly separate to break a circuit automatically immediately after said holder is struck.

In testimony whereof, I have signed my 50 name to this specification, in the presence of two subscribing witnesses.

OTTO L. HEEGER.
